FLUORESCENT LAMP

Herbert Tang Wing-Hing, 326 Kwun Tong Road,
Kwun Tong, Kowloon, Hong Kong

Filed June 5, 1974, Ser. No. 476,923

Term of patent 14 years

Int. Cl. D26—02

U.S. Cl. D48—24 R

FIG.1

FIG.2

FIG.3

FIG.4

FIG.5

FIG.6

FIG.7

FIG.8

FIG. 1 is a perspective view of a fluorescent lamp, showing my new design;

FIG. 2 is a front elevational view on an enlarged scale;

FIG. 3 is a right side elevational view on an enlarged scale;

FIG. 4 is a rear elevational view on an enlarged scale;

FIG. 5 is a top plan view on an enlarged scale;

FIG. 6 is a bottom plan view on an enlarged scale;

FIG. 7 is a sectional view along line 7—7 of FIG. 3; and

FIG. 8 is a sectional view along line 8—8 of FIG. 3.

I claim:

The ornamental design for a fluorescent lamp, substantially as shown and described.
